UNITED STATES PATENT OFFICE

2,324,649

REFRIGERATING APPARATUS

Nelson J. Smith, Dayton, Ohio, assignor to General Motors Corporation, Dayton, Ohio, a corporation of Delaware

Application January 24, 1941, Serial No. 375,825

10 Claims. (Cl. 62-89)

My invention relates to refrigerating apparatus and particularly to household refrigerators.

An object of my invention is to provide an improved refrigerator wherein sections or compartments thereof are maintained at different temperatures relative to one another for the proper preservation of various types of food products.

Another object of my invention is to provide an improved compartment within a household refrigerator cabinet for the purpose of maintaining food, such as butter and the like, at a temperature suitable for the preservation thereof, but higher than that within the main refrigerated food storage chamber of the cabinet in order to facilitate cutting and spreading of the butter upon use thereof.

A further object of my invention is to provide within the insulated walls of the food storage chamber of a refrigerator cabinet an auxiliary compartment which is warmed by inherent characteristics of a closed refrigerating system associated with the refrigerator.

A still further and more specific object is to provide an improved apparatus for and method of carrying out the invention set forth in the preceding objects, which method consists in utilizing a well-known characteristic of a refrigerating system to apply heat to an auxiliary butter and the like storage compartment disposed within the main refrigerated food storage chamber of a refrigerator cabinet while the refrigerating system operates to maintain a low temperature in the chamber.

Further objects and advantages of my invention will become apparent as the following description proceeds, and the features of novelty characterizing my invention will be pointed out with particularity in the claims annexed to and forming a part of the specification.

In the drawing:

Fig. 1 is a diagrammatic showing of a refrigerating system to be associated with a refrigerator cabinet adapted to have my invention incorporated therein;

Fig. 2 is a front view of a refrigerator cabinet having my invention incorporated therein with the refrigerating system disclosed in Fig. 1 mounted in the cabinet;

Fig. 3 is an enlarged vertical sectional view taken on the line 3-3 of Fig. 2 showing a compartment within the refrigerated food storage chamber of the refrigerator cabinet; and

Fig. 4 is an enlarged sectional view taken on the line 4-4 of Fig. 3 showing a portion of the

refrigerating system associated with the cabinet disposed in heat exchange relation with the compartment located in the food storage chamber.

- 5 It is well known that in order to properly preserve food stuffs in a domestic refrigerator it is necessary to maintain a temperature therein so low that butter stored therein is too hard to permit cutting and spreading thereof immediately 10 after removal of the butter from the refrigerator. For this reason, butter, for example, stored in the conventional refrigerator cabinet is usually removed from the cold storage chamber thereof long prior to serving in order that it may become warm to facilitate cutting and spreading thereof at the table. This procedure is not in conformity with the best of sanitary 15 conditions and, in addition, the housewife frequently forgets to carry out this procedure. Therefore, I contemplate the provision of means 20 whereby the butter can be kept in a sanitary condition substantially at all times and is ready to be cut, spread or served at the moment it is removed from the refrigerator. In carrying out 25 this feature, I utilize an inherent characteristic of the refrigerating system associated with the refrigerator cabinet.

In order to illustrate my invention I have shown diagrammatically in Fig. 1 of the drawing a closed refrigerating system including a sealed motor-compressor unit 11, the compressor of which withdraws evaporated or gaseous refrigerant from an evaporator 12, through a conduit 13, to cause the evaporator to produce a refrigerating effect. The compressor portion of the sealed motor-compressor unit 11 compresses the gaseous refrigerant withdrawn from evaporator 12 and forwards same under pressure to a condenser 14, through a conduit 15, where it is cooled and liquefied in any suitable or well-known manner. The condensed liquefied refrigerant collects and is stored in the lower portion of the condenser 14. Liquid refrigerant flows from condenser 14, through a conduit 16, into the evaporator 12, under control of a restrictor or restricting device 17, for reevaporation therein to permit the evaporator to continue to produce its refrigerating effect. Conduit or pipe 16 includes a portion formed into a flat serpentine-like coil 18 for a purpose to be hereinafter more fully described. The coil 18 has its inlet end connected with pipe 16 by a conduit portion 19 and has its outlet end connected to the restrictor 17 by a conduit 21. Starting and stopping operations of the motor-compressor unit 11 may be con-

trolled by a snap-acting switch 22 interposed in the electric circuit leading to the unit 11. Switch 22 is actuated in response to the temperature of evaporator 12 to make or break the electric circuit. Thus, I provide a thermostat bulb 23 in heat exchange relation with the evaporator 12 and connect this bulb 23, by a pipe 24, with an expansible and contractible bellows 25 which forms a part of the switch 22. In a system of the type described, the motor-compressor 11 and condenser 14 form a refrigerant compressing and liquefying unit, and the volatile refrigerant in such a system is liquefied by removing heat of compression and the latent heat of condensation from the refrigerating fluid compressed by the compressor. Liquefied refrigerant passing through pipe 16 to the flow control means or restrictor 17 or flowing toward evaporator 12 inherently has a sensible heat, which is the temperature of the liquid refrigerant after having the heat of compression and the latent heat of condensation removed from the compressed refrigerating fluid, that is above room temperature. Under ordinary conditions, this liquefied refrigerant is at a temperature of from 10° to 20° F. above room temperature, while the temperature within the refrigerated compartment of a cabinet being cooled by the refrigerating system is at approximately 40° or 45° F. Expansion of the condensed refrigerant fluid from the restrictor 17 into the low pressure side or evaporator 12 of the refrigerating system reduces the temperature of the restrictor to cool fluid entering the same. However, the refrigerating fluid in pipe 16 from the entrance side or end of the restrictor 17 to the condenser 14 is warm and the heat emitted from coil 18 in pipe 16 is inherent in the refrigerating system. Therefore, this characteristic of the refrigerating system is utilized for the purpose set forth in the objects of the present disclosure.

Referring now to Fig. 2 of the drawing, I have disclosed a household or domestic refrigerating apparatus which includes a cabinet generally represented by the reference character 30 and having a closed refrigerating system, of the type just described, associated therewith. Cabinet 30 includes metal outer panels or walls 31, an inner metal liner 32 and any suitable or desirable insulating material 33 (Figs. 3 and 4) disposed therebetween and forming insulated walls of a food storage chamber 34 within the cabinet. The outer metal panels or walls 31 of cabinet 30 depend beyond the insulated chamber 34 and provide a machine compartment therebelow which has its front normally closed by a door 36. Outer cabinet wall 31 and liner 32 are provided with registering apertures which provide an access opening for the food storage chamber 34 that is normally closed by a pivotally mounted insulated door structure 31. The evaporator or cooling element 12 of the refrigerating system disclosed in Fig. 1 is mounted in any suitable manner within the upper portion of the food storage chamber 34 and the refrigerant liquefying and circulating portion of the refrigerating system comprising unit 11, condenser 14 and switch 22 is normally disposed in the machine compartment of cabinet 30 and located behind the front closure or door 36 thereof. The refrigerant conveying pipes or conduit means 13 and 16 pass through the upper portion of the back wall of chamber 34 and extend down the back of cabinet 30 into the machine compartment housing the refrigerant liquefying and circulating portion or unit of the

refrigerating system. Operation of the refrigerating system causes evaporator 12 to produce a refrigerating effect within chamber 34 of cabinet 30 to cool and cause circulation of air therein.

According to the present invention, I provide a partition or means within the refrigerated food storage chamber 34 of the refrigerating apparatus which forms a compartment therein and which isolates the compartment from the cool air within the refrigerated food storage chamber. The coil 18 provided in pipe 16 of the refrigerating system is associated with the partitioning means so as to be in heat exchange relation with the compartment located in the food storage chamber. A partitioning means including a horizontal wall portion 41 and a vertical wall portion 42 is mounted intermediate the evaporator 12 and a side wall of liner 32. The wall portions 41 and 42 of the partition cooperate with the top, side and back walls of liner 32 or chamber 34 to form a compartment 43 in the upper part of the food chamber. Wall portions 41 and 42 of the partition may be formed of any suitable or desirable material and are preferably formed of molded insulating material. A door 46 may be secured to one of these partition wall portions to form an enclosure which isolates the compartment 43 from the cool air within the food storage chamber 34. Ample space is provided between the front of compartment 43 and the inner face of chamber door 31 to permit door 46 of the compartment 43 to be left partially open. Thus this compartment door 46 serves as a movable portion of the shielding walls for admitting some cool air from chamber 34 into compartment 43 and in thermal association with a receptacle adapted to be located therein when it is desired to lower the temperature within the compartment. Suitable clamps or supports 47, secured to liner 32 by screws or the like, may be provided for supporting the compartment-forming partitioning means within the upper part of chamber 34. Pipe coil 18 of pipe or conduit 16 of the refrigerating system is located immediately above the horizontal wall portion 41 of the partitioning means so as to be in intimate heat exchange relation with the interior of compartment 43. A plate or the like member 48 may be secured to coil 18 or it may be constructed as a part of the partitioning or shielding wall portions 41 and 42 to form a flat support within compartment 43 for the reception of a container or receptacle 49. Suitable provisions are made to extend the integral pipe portions or connections 19 and 21 of pipe 16 into and out of the compartment 43. The receptacle 49 is relatively long and narrow and preferably of a capacity to contain two one-pound cakes of butter or the like indicated by the reference character 51. In the operation of the refrigerating system of the apparatus disclosed, evaporator 12 produces a refrigerating effect within chamber 34 suitable for the cold storage of food placed therein. Since the sensible heat of liquid refrigerant flowing into or through pipe coil 18 from the condenser 14 of the refrigerant compressing and liquefying unit, by way of conduit 16, toward the evaporator 12 is at a temperature above room temperature, some of this sensible heat is dissipated into the auxiliary compartment 43 through receptacle support 48 to thereby apply heat to the heating element 18 and to the interior of compartment 43 to heat the butter or the like 51 stored therein. Thus, the refrigerating system is constructed and arranged to utilize the sensible heat of liquid refrigerant

flowing toward the evaporator for applying heat to a receptacle support or to an isolated compartment to render the refrigerator suitable for the storage of various food products without loss of efficiency to the refrigerating system. Compartment 43 being isolated from the cool air within the food storage chamber 34 and being warmed in the manner described insures that butter stored therein will be in proper condition to permit its being cut and spread at any time it is removed from its storage compartment within the refrigerator.

From the foregoing it will be apparent that I have provided a refrigerating system which cools a food storage chamber of a refrigerator cabinet to preserve foods placed therein and have provided a compartment within the cold storage chamber of the cabinet for the storage of butter and the like while, at the same time, constructing and arranging a portion of the refrigerating system in a novel and unique manner so as to utilize an inherent characteristic of the system for warming the auxiliary butter storage compartment. My invention permits the proper storage of various food products within a single apparatus and all of which products are readily accessible to facilitate the preparation and serving of meals.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination, a cabinet having a food storage chamber therein, a closed refrigerating system associated with said cabinet and containing a volatile refrigerant, said closed system including a refrigerant compressing and liquefying unit operatively connected with an evaporator disposed in said cabinet and adapted to cool air within said chamber, means within said chamber and forming a support for a receptacle therein, an element adapted to apply heat to said receptacle support, and said refrigerating system being arranged to utilize the sensible heat of liquid refrigerant flowing from said unit toward said evaporator for applying heat to said heating element.

2. A refrigerating apparatus comprising in combination, a cabinet having a food storage chamber therein, a closed refrigerating system associated with said cabinet and containing a volatile refrigerant, said closed system including a refrigerant compressing and liquefying unit operatively connected with an evaporator disposed in said cabinet and adapted to cool air within said chamber, means within said chamber and forming a support for a receptacle therein, and said refrigerating system having a portion thereof intermediate said unit and said evaporator disposed in heat exchange relation with said receptacle support for utilizing the sensible heat of liquid refrigerant flowing toward said evaporator to apply heat to said portion of said system.

3. A refrigerating apparatus comprising in combination, a cabinet having a plurality of insulated walls forming a food storage chamber therein, a closed refrigerating system associated with said cabinet and containing a volatile refrigerant, said closed system including a refrigerant compressing and liquefying unit operatively connected with an evaporator disposed in the up-

per portion of said chamber and adapted to cool air therein, a partition disposed within said chamber and located between said evaporator and a side wall of the chamber, said partition cooperating with the top wall of said chamber to form a compartment within the chamber isolated from the cool air therein, and said partition having a portion of said refrigerating system intermediate said unit and said evaporator associated therewith for utilizing the sensible heat of liquid refrigerant flowing toward said evaporator to apply heat to the interior of said compartment.

4. A refrigerating apparatus comprising in combination, a cabinet having a food chamber therein, a refrigerant liquefying apparatus associated with said cabinet, wall structure arranged to form a compartment within said chamber insulated from the air in the latter, and means in heat exchange relation with said compartment for transferring to the compartment from the refrigerant heat developed in the latter by the operation of said liquefying apparatus thereon.

5. In a refrigerator cabinet having a refrigerated chamber, a refrigerant circulating system for providing refrigeration therein, a thermally insulated compartment within said refrigerated chamber, one wall of said compartment comprising spaced apart members, the inner of said spaced apart members being formed from material having relatively good heat conducting characteristics, and means associated with said inner member and the refrigerant circulating system for conducting heat from a portion of said system to said inner member.

6. In a refrigerator cabinet having a refrigerated chamber, a refrigerant circulating system for providing refrigeration therein, a thermally insulated compartment within said refrigerated chamber, one wall of said compartment comprising spaced apart members, the inner of said spaced apart members being formed from material having relatively good heat conducting characteristics, means associated with said inner member and the refrigerant circulating system for conducting heat from a portion of said system to said inner member, and the outer of said spaced apart members being formed from a material having relatively good heat insulating qualities.

7. In a refrigerator cabinet having a chamber therein, a refrigerant circulating system including an evaporator for cooling air within said chamber, a food storage receptacle in said chamber, means containing a volatile fluid thermally associated with said receptacle for transferring thereto heat from a suitable source thereof, and shielding means substantially enclosing said receptacle and normally maintaining the cool air within said chamber out of thermal association therewith.

8. In a refrigerator cabinet having a chamber therein, a refrigerant circulating system including an evaporator for cooling air within said chamber, a food storage receptacle in said chamber, means associated with said receptacle and the refrigerant circulating system for conducting heat from a portion of said system to said receptacle, and shielding means substantially enclosing said receptacle and normally maintaining the cool air within said chamber out of thermal association therewith.

9. In a refrigerator cabinet having a chamber therein, a refrigerant circulating system including an evaporator for cooling air within said chamber, a food storage receptacle in said chamber,

ber, a heat dissipating portion of said refrigerant circulating system being in thermal association with said receptacle for transferring heat there-to, and shielding means substantially enclosing the said receptacle and normally maintaining the cool air within said chamber out of thermal association therewith.

10. In a refrigerator cabinet having a chamber therein, a refrigerant circulating system includ-ing an evaporator for cooling air within said chamber, a food storage receptacle in said cham-

ber, means associated with said receptacle and the refrigerant circulating system for conducting heat from a portion of said system to said recep-tacle, means forming a shield about said recep-tacle for protecting same from the cool air within said chamber, and said shield including a por-tion movable relative to other portions thereof for admitting said air into thermal association with said receptacle.

NELSON J. SMITH.
